UNITED STATES PATENT OFFICE

156,593

CIGARETTE HOLDER

Anthony T. Angerer, Girard, Pa.

Application March 31, 1949, Serial No. 1,726

Term of patent 3½ years

(Cl. D85—8)

To all whom it may concern:

Be it known that I, Anthony T. Angerer, a citizen of the United States, residing at Girard, in the county of Erie and State of Pennsylvania, have invented a new, original, and ornamental Design for a Cigarette Holder, of which the following is a specification, reference being had to the accompanying drawing, forming part thereof.

I claim:

The ornamental design for a cigarette holder, as shown.

ANTHONY T. ANGERER.
